UNITED STATES PATENT OFFICE.

FITZ WILLIAM SARGENT, OF MAHWAH, NEW JERSEY, ASSIGNOR TO THE AMERICAN BRAKE SHOE AND FOUNDRY COMPANY, OF WILMINGTON, DELAWARE, A CORPORATION OF DELAWARE.

BRAKE-SHOE.

1,328,594.

Specification of Letters Patent.

Patented Jan. 20, 1920.

Application filed July 8, 1919. Serial No. 309,345.

To all whom it may concern:

Be it known that I, FITZ WILLIAM SARGENT, a citizen of the United States, and a resident of Mahwah, in the county of Bergen and State of New Jersey, have made and invented certain new and useful Improvements in Brake-Shoes, of which the following is a specification.

My invention relates to brake shoes designed to be used with railway and similar vehicles, and particularly to brake shoes of the type or class wherein a body portion made from cast metal, or cast metal having other material embedded therein, is used in connection with a back made of wrought metal or mild steel, the purpose of the back being to hold the parts of the shoe together in case the same should be broken into one or more pieces, as frequently happens when the shoe is in use.

Heretofore in making brake shoes having a wrought metal or steel back the usual practice has been to support the back within the cavity of the mold into which the cast metal is poured to form the body portion of the shoe, whereupon and when the molten cast metal is poured into the mold cavity the wrought metal or steel back becomes embedded in the rear surface or back of the shoe. This practice, however, results in heating the back to a high temperature, and frequently in burning or otherwise injuring the same to such an extent as to materially weaken it. Furthermore, in such cases stresses are produced within the body of the shoe as the same cools, due to the presence of the back therein; because of the fact that the back is not heated to as high a temperature as the molten metal poured into the mold, and the fact that the body portion contracts more rapidly than the back during the cooling of the shoe.

The cooling of the body portion after the molten metal has become solid thus results in a gripping action upon the back as the body portion continues to contract, which action sets up stresses within the body of the shoe tending to crack the body metal along a plane extending longitudinally of the shoe; it having been found in practice that shoes are frequently split in the man-

ner indicated, due to the internal stresses which were set up as the shoe cooled and contracted against the unyielding side edges of the back when the shoe was cast.

It will be further apparent that a wrought iron or steel back embedded in the rear face of a brake shoe as above pointed out cannot be removed therefrom and used again, and that when the shoe is worn out such portions of the body portion as may still adhere thereto, as well also as the wrought metal back, have to be discarded as scrap material.

In order to avoid the objections above pointed out and as distinguished from the old method of construction referred to, my invention consists of the wrought iron or steel back portion which is made separate from the body portion, and is assembled therewith after the body portion has been formed; this result being secured by providing the body portion with a longitudinally extending groove dove-tailed in form, or having overhanging side walls, along which groove the back may be driven in assembling the parts, the cross section of the back obviously corresponding with that of the groove in which it fits; the term "dove-tail" or "undercut" referring to a downwardly enlarging opening.

The steel back of my improved brake shoe in addition co-operates with the body portion and with the key lug so as to secure the said attaching or key lug and the shoe together and in their assembled condition; the key lug being also made separate from the body of the shoe, and the same being provided with a base portion which fits in a transverse groove or recesses provided in the body portion and is locked in place relative to the body portion by the back as the same is assembled with the body portion of the shoe to thereby hold all the parts thereof interlocked one with the other.

With the object in view of avoiding the objections above noted, and providing a brake shoe wherein the back and attaching lug are formed separately from the body of the shoe and are interlocked one with the other when the shoe is assembled, my invention consists in the improved brake shoe illustrated in the accompanying drawing

and hereinafter described and claimed, and in such variations and modifications thereof as will be obvious to those skilled in the art to which my invention relates.

5 In the drawing accompanying and forming a part of this specification, and wherein the preferred embodiment of my invention is illustrated:

Figure 1 is a view partly in side elevation and partly in section upon a plane extending longitudinally thereof of a brake shoe made in accordance with my invention;

10 Fig. 2 is a plan view showing my improved brake shoe, a portion of the key lug and a portion of the back being broken away to show features which would otherwise be hidden;

15 Fig. 3 is a view showing a section upon a transverse plane indicated by the line 3—3, Fig. 1;

20 Fig. 4 is a view showing a section taken upon a transverse plane indicated by the line 4—4, Fig. 1, looking toward the right;

25 Fig. 5 is a fragmentary view showing one construction of back whereby the same may be secured against longitudinal movement relative to the body portion of the shoe, this being the form of back used in the embodiment of my invention illustrated in Figs. 1, 2 and 4.

30 Fig. 6 is a fragmentary view showing an alternative method of securing the back against movement longitudinally of the shoe;

35 Fig. 7 is a view showing a section upon a longitudinally extending plane indicated by the line 7—7, Fig. 6;

40 Fig. 8 is a view showing the end portion of the back shown in Figs. 6 and 7 before the same is bent over to form a loop shown in said figures;

45 Fig. 9 is a view partly in side elevation and partly in section upon a longitudinally extending plane of an embodiment of my invention in which a key lug integral with the body of the shoe is used;

50 Fig. 10 is a view showing a section upon a transverse plane indicated by the line 10—10, Fig. 9;

55 Fig. 11 is a view similar to Fig. 9 but showing the key lug as made from a suitable wrought metal blank bent so as to provide a form of lug commonly referred to as of the box type;

Fig. 12 is a view showing the shoe shown in Fig. 11 in plan; and,

Fig. 13 is a view showing a section upon a transverse plane indicated by the line 13—13, Fig. 11.

60 Referring to the drawing, the reference numeral 10 designates the body portion of my improved brake shoe; the same being ordinarily made from cast iron, or from cast iron in which inserts of other material are

70 embedded to thereby produce a brake shoe having a more effective braking action, better wearing qualities, or which is otherwise better suited for the service for which it is designed.

The rear face of the body portion 10 is provided with a longitudinally extending dove-tailed groove 11, the two ends of which are open and unobstructed, as shown in Figs. 1, 2 and 12; and the bottom wall of this 75 groove is provided with one or more recesses 12 located adjacent the ends of the shoe, and preferably with one or more recesses 13 located at the central portion of the shoe.

80 The reference numeral 14 designates a back made from wrought iron, mild steel, or similar material, and which back corresponds in cross section with the cross section of the dove-tailed groove 11 in which it is designed to fit. The end portions of this 85 back in the form thereof shown in Figs. 1, 2, 4 and 5 are slotted, at 15, Fig. 5, and the portion 16 of reduced width thus cut free is so shaped as to provide a hump or lug 17. This lug is commonly formed before the 90 back is assembled with the shoe, and the free end 18 of the portion 16 then lies above the plane of the under side of the back. After the back has been driven into place in the dove-tailed slot 11, however, the free 95 ends 18 of the lugs at each end of the back are forced downward, as by a blow from a hammer, and made to enter the recesses 12 in the back of the body portion, thereby preventing longitudinal movement of the back 100 relative to the body portion of the shoe.

Other portions of the back indicated by the reference numerals 19 are also preferably cut free from the same along all but one of their sides to thereby provide fastening lugs or tongues which may be driven downward and into the recesses 13 in the body of the shoe when the parts thereof are assembled, to thereby more effectively prevent the falling away of portions of the 110 body portion from the back should the body portion become broken when in use. It will be appreciated, however, that these last-mentioned lugs, as well as the recesses with which they coöperate, may be omitted 115 should it be deemed desirable to do so, as the fastenings provided by the end lugs 17 and the recesses 12 will be adequate in many services.

120 The lugs or humps 17 lie in between the toes or end supporting lugs of an ordinary standard type of brake head when the shoe is in use, and prevent sidewise movement of the ends of the shoe; and end lugs 20 are provided at the ends of the body portion 125 for taking up the thrust, due to the retarding action of the brake shoes, which is transmitted through the shoe to the brake head, when the brakes are applied, said lugs engaging with the end supporting lugs 130

of the ordinary standard type of brake head with which my improved brake shoe is designed to be used.

My improved brake shoe is secured to the 5 brake head whereby it is supported by a suitable attaching or key lug designated by the reference numeral 21 in Figs. 1, 2 and 3, the form thereof there shown having longitudinal openings 22 to accommodate the ordinary key whereby the shoe is secured to a 10 brake head. This attaching or key lug is made separate from the body portion 10 of the shoe; and the same is ordinarily made from malleable iron, wrought metal, or of a 15 metal which is tougher and stronger than the body portion of the shoe, in order to more effectively resist the strains to which the lug is subjected when the shoe is in use. The lug 21 is provided with a base portion 20 23 which fits within a transversely extending recess or groove 24 provided in the body portion 10, the groove and base being shown as dove-tailed in form in order to provide an interlocking connection between the key 25 lug and the body portion of the shoe. The base 23 of the lug is shown as provided with a dove-tailed recess 25 of such a width and so arranged as to register with the longitudinally extending groove 11 provided for 30 the back 14 when the lug is in place; from which it follows that when the key lug is properly assembled in the transverse groove 24 provided for it, and the back 14 is driven longitudinally along the groove 11 within 35 which it fits, the lug will be held in place relative to the body and all the parts of the shoe interlocked with one another; thereby providing an extremely strong connection between the parts of the shoe, all of which 40 are interlocked with one another and mutually secured together in the assembled shoe.

Figs. 6, 7 and 8 show a slightly modified scheme for preventing longitudinal movement of the back 14 after it has been introduced into the groove 11 provided for its reception, as hereinbefore explained. In this form of my invention the end of the back is provided with an extending portion or 45 tongue 26 of reduced width and which portion, after the back is in place relative to the body portion of the shoe, is bent about a pin 27 extending through the end lugs 28 of the body portion, thereby providing a loop 5 through which the pin extends and whereby longitudinal movement of the back is prevented.

In view of the premises it will be appreciated that the wrought metal or mild steel 0 back is an element entirely separate from the body portion of the shoe, and is assembled therewith after the body portion has been produced. It therefore follows that the back is not burned or otherwise injured during 5 the casting operation; and I may here re-

mark that I am enabled to use a back made from much thinner metal than has heretofore been possible, because of the fact that the same is in no way burned or injured by hot metal during the casting operation. It 70 will also be appreciated that the cost of providing a steel back for the body portion is greatly reduced, as the complicated and expensive molding operation heretofore necessary to position a back in a mold, and to hold it in place while the molten metal is poured thereinto, is entirely avoided; it having been found feasible in practice to form the groove in the back by the use of a simple core with sufficient accuracy to provide for the reception of the steel back subsequently driven thereinto, as a close and even bearing throughout the entire extent of the back is unnecessary in practice. Furthermore, the fact that the metal ordinarily employed to 85 form the back is quite thin permits the back to be driven into place, even though there be some irregularity along the side edges of the groove within which it fits.

It will be obvious that when the body portion of the shoe has been worn to such an extent as to be no longer serviceable the lugs 17 may be bent up, or the loops 28 opened, and the back driven out of the groove within which it lies with comparative ease; or 90 such portion or portions of the body as may still be attached to the back by the side walls of the groove may be broken away from the back; whereupon both the back and the attaching lug may be used with a new body 95 portion, as hereinbefore stated; it having been found feasible in practice to use a single lug and back with several successive body portions.

In the embodiment of my invention illustrated in Figs. 9 and 10 the steel or wrought iron back 14 is made separate from the cast metal body portion 10 of the shoe, and is slid along a dove-tailed groove provided in the rear face of the body portion in assembling the parts, the same as hereinbefore explained; after which the tongues or lugs 19 are forced into recesses 13 formed in the bottom of the groove within which the back lies to thereby prevent movement of the back 115 along the groove. The attaching or key lug 29, however, is integral with the body of the shoe, as best shown in Fig. 10; and the said lug is reinforced and in part formed by a bar bent to provide a top portion 30, depending sides 31, and hooks or toes 32, all except the middle portion of the top bar 30 being embedded in the cast metal from which the body of the shoe is formed. The sides of the steel back 14 overlie the toes 32 when 125 the back is in place, as best shown in Fig. 10, thereby greatly strengthening the lug and preventing the wrought iron or steel bar embedded in and forming a part thereof from pulling out from the body portion, and 130

the lug as a whole from being broken off from the body of the shoe.

Figs. 11, 12 and 13 show a form of my invention wherein a hollow lug of box-like form, and of a class or type commonly referred to as "box" lugs, is employed for supporting the shoe in a brake head. The lug shown is made from a suitable wrought iron or steel blank of general cross-shape 10 form and having portions which when bent downward form the end plates 33 of the lug, which plates provide extended bearings for the center lugs of the brake head whereby the shoe is supported; together with other 15 portions shown as bent downward to provide the sides 34 whereby the lug is attached to the body 10 of the shoe, and inward to form hooks or toes 35 which in effect constitute the base of the lug regarded in its entirety. 20 These base portions or lugs lie within transversely extending grooves or recesses 36 which, while shown as separated one from the other, may obviously take the form of a single recess or groove within which the 25 parts 35 which form the base of the key lug lie when the lug and body portion are assembled. The steel back 14 in this form of my invention overlies the lugs or toes 35 of the key lug when the parts of the shoe are 30 assembled, and serves to fasten the same to the body of the shoe; the said back fitting in a dove-tailed groove 11, and the same being prevented from longitudinal movement therein by lugs 19 depressed into recesses 13 provided in the bottom wall of 35 the groove, as will be understood. The end walls 33 are provided with holes 37 through which the key which fastens the shoe to the brake head extends and, while 40 the back is shown in Figs. 9, 11 and 12 as unprovided with guide lugs such as are provided by the humps 17 and the tongues 26 in the forms of my invention illustrated in Figs. 1 to 8, it will be appreciated that such 45 or other forms of guide lugs for preventing sidewise movement of the ends of the shoe will be provided should their presence be deemed necessary or desirable, and that such lugs are in fact commonly present in most 50 forms of brake shoes in use upon railway vehicles.

Having thus described and explained my invention, I claim and desire to secure by Letters Patent:

55 1. A brake-shoe comprising a body portion provided with a longitudinally extending groove on the rear face thereof and a plurality of pockets; a back fitting within said groove, and means formed in said back and adapted to be forced into said pockets to thereby retain the shoe and back 60 in their said positions.

65 2. In a brake shoe, a body portion having a longitudinally extending dove-tailed or undercut groove of uniform width through-

out; a back corresponding in width with the width of said groove and so shaped as to move longitudinally thereof in assembling the parts; means for locking said back against movement longitudinally of said 70 body portion; and an attaching lug whereby the shoe may be secured to a suitable brake head.

3. In a brake shoe, a body portion having a longitudinally extending dove-tailed 75 or undercut groove of uniform width throughout; a back corresponding in width with the width of said groove and so shaped as to move longitudinally thereof in assembling the parts; means carried by said 80 back and adapted to engage said body portion for locking the same against movement longitudinally of said body portion; and an attaching lug whereby the shoe may be secured to a suitable brake head. 85

4. In a brake shoe, a body portion having a longitudinally extending dove-tailed or undercut groove of uniform width throughout; a back corresponding in width with the width of said groove and so shaped as 90 to move longitudinally thereof in assembling the parts, and which back is provided with a portion adapted to be bent and made to engage the body portion to thereby lock the back in place and prevent longitudinal movement thereof within said 95 groove; and an attaching lug whereby the shoe may be secured to a suitable brake head.

5. In a brake shoe, a body portion having 100 a longitudinally extending dove-tailed or undercut groove; a back corresponding in width with the width of said groove and so shaped as to move longitudinally thereof in assembling the parts, and a portion of which 105 back is cut free therefrom to thereby provide a tongue; a recess formed in the bottom wall of said groove adjacent said tongue and into which the same may be depressed; and an attaching lug whereby the shoe may 110 be secured to a suitable brake head.

6. In a brake shoe, a body portion having end lugs spaced apart from one another and a longitudinally extending dove-tailed or undercut groove extending between said 115 lugs; a back corresponding in width with the width of said groove and so shaped as to move longitudinally thereof in assembling the parts and the end of which back is bent to provide a loop; a pin extending through openings provided in said end lugs and through said loop; and an attaching lug whereby the shoe may be secured to a suitable 120 brake head.

7. In a brake shoe, a body portion having 125 end lugs spaced apart from one another, and a longitudinally extending dove-tailed or undercut groove extending between said lugs; a back corresponding in width with the width of said groove and so shaped as to 130

move longitudinally thereof in assembling the parts, and the end of which back is provided with an extending portion of reduced width and which portion is bent to provide 5 a loop; a pin extending through openings provided in said end lugs and through said loop; and an attaching lug whereby the shoe may be secured to a suitable brake head.

8. In a brake shoe, a body portion having 10 a longitudinally extending dove-tailed or undercut groove; a centrally located key lug formed separately from said body portion and whereby the brake shoe may be secured to a suitable brake head; and a back corresponding 15 in width with the width of said groove and so shaped as to move longitudinally thereof in assembling the parts, and which back engages with said securing lug when the parts are assembled to thereby lock 20 said lug and body portion together.

9. In a brake shoe, a body portion having a longitudinally extending dove-tailed or undercut groove, and a transversely extending groove located adjacent the central portion of the shoe; a securing lug formed separately from said body portion and having a base portion lying within said transverse groove; and a back corresponding in width 25 with the width of said longitudinally extending groove and so shaped as to move longitudinally thereof in assembling the parts, the arrangement of the parts being such that the back engages with the said securing lug to thereby lock the parts of the 30 assembled shoe together.

10. In a brake shoe, a body portion having a longitudinally extending dove-tailed or undercut groove, and a centrally located transversely extending dove-tailed or undercut groove intersecting said first-mentioned groove; a key lug formed separately from said body portion and having a base adapted to fit within the transverse groove aforesaid; and a back corresponding in 45 width with the width of said groove and so shaped as to move longitudinally thereof in assembling the parts, the relative arrangement of the parts being such that the back engages with the base portion of the key lug 50 to thereby lock the parts together in the assembled shoe.

11. In a brake shoe, a body portion having a longitudinally extending dove-tailed or undercut groove, and a centrally located transversely extending dove-tailed or undercut groove intersecting said first-mentioned groove; a key lug formed separately from said body portion and having a base adapted 55 to fit within the transverse groove aforesaid, and a dove-tailed or undercut recess

adapted to register with the dove-tailed or undercut groove in said body portion when the lug is in place; and a back corresponding in width with the width of said groove and so shaped as to move longitudinally 65 thereof in assembling the parts, the relative arrangement of the parts being such that the back lies within the dove-tailed or undercut recess in the base portion of the key lug when the parts are assembled to thereby lock the parts together in the assembled shoe. 70

12. In a brake shoe, a body portion having a longitudinally extending dove-tailed or undercut groove, and transversely extending recesses located adjacent the central portion of the shoe and beneath the bottom wall of said groove; a securing lug formed separately from said body portion and having bottom or base portions lying within 75 said recesses; and a back corresponding in width with the width of said longitudinally extending groove and so shaped as to move longitudinally thereof in assembling the parts, and which back overlies the portions 30 of said securing lug which lie within said recesses when the parts of the shoe are assembled.

13. In a brake shoe, a body portion having a longitudinally extending dove-tailed or undercut groove; a key lug formed separately from said body portion and whereby the brake shoe may be secured to a suitable brake head; and a back corresponding in width with the width of said groove and so 95 shaped as to move longitudinally thereof in assembling the parts, and a portion of which back engages with a portion of the lug aforesaid to thereby fasten the lug to the shoe when the parts are assembled. 100

14. In a brake shoe, a body portion having a longitudinally extending dove-tailed or undercut groove; a key lug formed separately from said body portion and whereby the brake shoe may be secured to a suitable 105 brake head; a back corresponding in width with the width of said groove and so shaped as to move longitudinally thereof in assembling the parts, and a portion of which back overlies a portion of the lug aforesaid to 110 thereby fasten the lug to the shoe when the parts are assembled.

Signed at New York, borough of Manhattan, in the county of New York and State of New York, this 2nd day of July A. D. 115 1919.
